UNITED STATES PATENT OFFICE.

GEORGE E. HULSE, OF NEWARK, NEW JERSEY.

PIPE.

Application filed December 11, 1919. Serial No. 344,118.

This invention relates to tobacco pipes and the like. One of the objects thereof is to provide a simple construction of tobacco pipes and the like which will improve their smoking action and tend to purify the smoke. Another object is to provide a construction of the above type which shall be readily maintained in efficient working condition. Another object is to provide a construction of the above type which shall be inexpensive and yet durable. Other objects will be in part obvious and in part pointed out hereinafter.

The invention accordingly consists in the features of construction, combinations of elements and arrangements of parts which will be exemplified in the structure herein-after described and the scope of the application of which will be indicated in the following claims.

In the accompanying drawing in which is shown one of various possible embodiments of this invention,

Figure 1 is a longitudinal vertical section through the same;

Figure 2 is a side elevation of a device incorporated in the pipe and shown on a smaller scale in Figure 1;

Figure 3 is a top plan view of the device shown in Figure 2 with a diagrammatic sectional representation of the walls of the pipe associated therewith;

Figure 4 is a cross-section along the line 4-4 of Figure 3; and

Figure 5 is a cross-section along the line 5-5 of Figure 3.

Similar reference characters refer to similar parts throughout the views of the drawing.

Referring now to Figure 1 of the drawings, there is shown a pipe body 10 comprising the bowl 11 and extension 12. The latter is hollow to provide an opening or passage of the general cylindrical shape and has fitted therein a device 13, better shown in Figures 2 and 3 of the drawing. This device, which is preferably constructed of metal although it may be formed of other material, comprises an end portion 14 fitting the inner end of the extension 12, as shown in Figure 1. The opposite end of this device is preferably given a tapered form as at 15 to fit the walls at the outer end of the extension.

This part 15 is provided with an outward flange 16 the surface of which may be

knurled, and with an inner tapered recess 17 into which is fitted the tapered end of the stem 18.

Between the end portions 14 and 15 of the device 13 is an intermediate portion which is so shaped as to have a large number of substantially parallel projections 19 engaging the corresponding portions of the inner walls of the pipe body, indicated at 20. These projections may be formed as by a thread cut about the device and interrupted as hereinafter described and as shown in Figure 3 of the drawing, and provide a large number of minute passages 21 extending in a general direction transverse to the axis of the stem of the pipe. At the upper and lower sides of this intermediate portion of the device, it is flattened as shown at 22 and 23, and when in position forms the corresponding chambers 24 and 25.

The inner end portion 14 is provided with an inclined passage 26 leading from the bowl of the pipe to the lower chamber 25, and the upper end portion is provided with an inclined passage 27 leading from the upper chamber 24 to the passage through the stem of the pipe.

It may be noted at this point that although the device positioned as shown in the pipe possesses certain advantages peculiar to such position, nevertheless many of the advantages of this invention may be attained with the device turned about its axis into other positions and even inverted.

Taking up now the action of this pipe, the smoke is drawn through the passage 26 into the lower chamber 25, thence divided into a large number of minute currents corresponding to the passages 21, into the upper chamber 24. In the latter chamber the smoke passes downwardly through the passage 27 and out through the stem in the usual manner. Considering the mechanical effect of this action, the device normally acts as a strainer tending to segregate all particles of foreign matter before the passage of the smoke through the stem. Also the passage of saliva in the reverse direction into the bowl of the pipe is substantially prevented by the form of the passages through which the smoke is led. Another function of this device, particularly evident if it is of metal, is its tendency to condense injurious ingredients of the smoke upon its outer surface and prevent their being car-

ried out through the stem. When the strainer becomes fouled in use it is readily withdrawn and in this action the end portion 14 acts as a scraper to cleanse the entire inner walls of the extension 12 of the pipe body. Also inasmuch as substantially the entire smoke passage with respect to this device is on its outer surface, it may be instantly cleansed and replaced. It is furthermore to be noted that the renewal of no parts is required as the entire device is of a permanent nature.

It will thus be seen that there is provided a device in which the several objects of this invention are achieved and that it is of an essentially practical nature.

As various possible embodiments might be made of the above invention and as various changes might be made in the embodiment above set forth, it is to be understood that all matter herein set forth or shown in the accompanying drawing is to be interpreted as illustrative and not in a limiting sense.

I claim as my invention:

1. In construction for tobacco pipes and the like, in combination, a bowl member having a substantially cylindrical hollow portion, and a device removably fitted within said hollow portion engaging the walls thereof adjacent each of its ends, the intermediate portion thereof being flattened on opposite sides and the surface thereof between the flattened sides substantially fitting the walls of said hollow portion and transversely recessed, said device thus forming with the wall of said hollow portion a

pair of opposite chambers connected by said recesses and respectively connected with the bowl and with the stem of the pipe.

2. In construction for tobacco pipes and the like, in combination, a body member having a substantially cylindrical passage, a strainer member within said passage fitting the walls thereof adjacent its ends, said strainer member being substantially flattened on opposite sides to provide corresponding chambers and having a plurality of substantially parallel recesses in its surface intermediate said flattened sides, the edges of which recesses substantially engage said walls, and having passages respectively connecting said chambers with the bowl and with the stem of the pipe, and a stem member removably secured at the outer end of said device.

3. In construction for tobacco pipes and the like, in combination, a body member having a bowl associated therewith and provided with a main chamber, a stem member, means adapted to be inserted into said chamber and to divide said chamber into a lower chamber connecting with said bowl and an upper chamber connecting with said stem, and a plurality of grooves exteriorly formed in said means and adapted to form with the interior walls of said main chamber a plurality of passages connecting said upper and lower chambers.

In testimony whereof, I have signed my name to this specification this third day of December, 1919.

GEORGE E. HULSE.
